FLASHING BLOCK

William F. Cox, Winston-Salem, N. C.

Application October 22, 1936, Serial No. 107,047

5 Claims. (Cl. 108—26)

This invention relates to improvements in a flashing block and more especially to a flashing block having an inclined slot therein which is adapted to receive a hooked end of flashing to lock the same into position.

More particularly, the invention contemplates a flashing block provided with a slot for receiving flashing with means disposed in the slot for locking the flashing in position and also means disposed within the slot for releasing said locking means so that the flashing may be removed therefrom.

It is a well known fact that ordinary flashing does not withstand the weather as well as the better grades of roofing, consequently, it frequently becomes necessary to remove the flashing and replace it with new flashing. Heretofore, great difficulty has been encountered in removing this flashing without damaging or destroying the flashing block because the flashing, when once placed therein, and locked in position, could not be very easily removed.

It is therefore, an object of this invention to provide a flashing block for roof flashing which is adapted to be laid in a wall with the exterior surface thereof flush with the surface of said wall, said block having a slot therein to receive the flashing and said slot having a re-entrant portion communicating with the slot to receive a projection on the flashing. Cam means are also provided within this block for bending the hooked portion of the flashing upon itself to cause the flashing to be automatically released from the flashing block without damaging the block.

Some of the objects of the invention having been stated, other objects will appear as the description proceeds when taken in connection with the accompanying drawings, in which:

Figure 1 is an isometric view showing a portion of a parapet wall and its junction point with a roof showing my invention applied thereto;

Figure 2 is an enlarged, sectional view taken along line 2—2 in Figure 1;

Figure 3 is an exploded isometric view of a flashing block used in Figure 1 showing the cap flashing and the base flashing removed therefrom;

Figure 4 is an enlarged sectional view through the flashing block shown in Figure 3 but showing the cap flashing in the position which it occupies prior to its being removed therefrom;

Figure 5 is an isometric view of a portion of a modified form of flashing block;

Figure 6 is an isometric view of the cap flash-

ing which is adapted to be placed in the block shown in Figure 5;

Figure 7 is an enlarged, cross-sectional view of the block shown in Figure 5 showing the flashing in the position which it normally occupies when installed upon a roof of a building;

Figure 8 is an enlarged cross-sectional view similar to Figure 7 but showing the cap flashing in the position immediately before it is removed, and also showing a suitable tool inserted therein to assist in its removal.

Referring more specifically to the drawings, the numeral 10 denotes a suitable parapet wall of a building which is adapted to support one end of roof beams 11. The roof beams 11 have ordinary sheathing 12 secured thereon which, in turn, supports the roofing material 13. At the junction point of the parapet wall 10 and the roofing material 13 it is necessary to provide a suitable construction for the prevention of leaks.

The most commonly used method for preventing leaks is to provide suitable flashing disposed at this point so that the moisture or water which might fall upon the sides of the parapet wall 10 will be conducted downwardly upon roof 13 and into gutter 15.

I have provided a special flashing block 16 which is adapted to be placed at the desired points within the parapet wall 10. Since the roof shown in Figure 1 is inclined, it is obviously necessary to place the flashing blocks 16 in a stair step formation on the interior surface of the wall with the inclined slot 17 in the face thereof disposed on the interior of the wall adjacent the roof.

It will be noted in some instances these flashing blocks 16 are placed so that the slots 17 are in line with each other in order to accommodate a flashing which is of a greater length than the flashing block. It is to be understood, however, that any length of flashing desired may be used with the particular flashing block. In cases where the roof is comparatively level or where its intersection with the wall is parallel with the mortar joints in the brick wall, the flashing blocks may replace one row of bricks and the entire length of flashing inserted in the block at one time after it has been riveted together. In any event the principle of construction of the flashing block and the principle used in removing the flashing from the block and locking it therein is essentially the same.

It will be noted by referring to Figures 2, 3 and 4, that the inclined slot 17 is narrowed or

restricted as at 17a until its width is only slightly greater than twice the thickness of the cap flashing 18 plus the thickness of the base flashing 19. It will also be noted that the slot 17 has a re-entrant portion 20 and a cam surface 21. When installing the flashing, the base flashing 19 is inserted into slot 17 with its upper edge extending into the restricted portion 17a as shown in Figures 2 and 4. It is then bent downwardly 5 beside the wall 10 at the mouth of slot 17 and again bent laterally at the roof line so as to fit directly on top of the sheathing 12. The roofing 13 is placed over this outstanding leg of the base flashing 19, thereby insuring that no water 10 will be allowed to penetrate the roof. The cap flashing 18 is bent as at 23 and also as at 24 15 forming a hooked portion 25 on the end of the flashing. The overall width of this hooked portion is slightly greater than the width of the slot 20 17, however, a small amount of inherent resiliency is present in the average flashing so that when it is desired to insert the hooked portion 25 of cap flashing 18 in the slot 17, the hooked portion will spring upon itself a sufficient amount 25 to allow this portion to be inserted within the slot. After the hooked portion 25 has been inserted into the slot and moved upwardly, the hooked edge snaps into re-entrant portion 20 and is thereby locked into position. Then the 30 flashing is bent as at 26 downwardly on the outside of the main flashing 19. After this has been done a suitable calking material 27, such as tar, asbestos and the like, is inserted into slot 17 to fasten and seal the parts in position. If 35 for any reason, it is desired to remove the cap flashing 18 from the slot, it is only necessary to remove the calking material and bend the flashing at the point 26 again until the lower portion thereof occupies substantially the same plane as 40 the other portion which is disposed within slot 17. Then the flashing is bodily pushed to the left in Figures 2 and 4 until the upper hooked portion 25 engages the cam surface 21. The hooked portion 25 is then bent downwardly 45 against the other portion of the flashing to cause it to occupy less overall space. After it has been inserted in the position shown in Figure 4, the parts will not return to their normal position 50 since the materials from which ordinary flashing is made does not have a high degree of spring action or resiliency. It is quite evident that the flashing member 18, together with the crushed hook portion 25 at this time may be withdrawn 55 from the slot 17 without the use of any tool or without destroying the flashing block.

Figures 5 to 8 inclusive, show a slightly modified form of block in which an inclined flared slot 30 is provided in the flashing block 31 which slot has communicating with the upper portion 60 thereof the re-entrant portion 32. Also disposed in the upper portion of said slot is a suitable projection 33. The base flashing 34 is inserted within this slot as described in the preceding form, and then the cap flashing 35 is 65 inserted therein. When it has been inserted to the proper position the hooked end 36 snaps into the recess 32 to cause the parts to assume the position as shown in Figure 7, after which, a suitable calking material 37 is placed in the 70 slot 30 to tighten and seal the flashing into position. When it is desired to remove the flashing the cap flashing 35 is pushed upwardly to the position shown in Figure 8 to a point where the end of a suitable tool such as a screw driver 75 39 may be inserted therein to guide the hooked

end in its proper position while the flashing is being withdrawn. The projection 33 serves to cause the hooked end to bend downwardly in Figure 8 in case it is necessary for this to be done in order to allow the point of the tool 39 to be placed above this hooked portion. However, under ordinary conditions the projection 33 is not necessary since the upper end of slot 30 is flared so that the tool may be inserted therein so that the upper edge of the tool will rest above the 10 hooked portion 36 when it is in the position shown in Figure 8.

It is therefore, seen that I have provided a 15 flashing block having an inclined slot therein with a re-entrant portion communicating with said slot for receiving and locking the end of the flashing therein, and also cam means for releasing said flashing so that the same may be removed from said slot.

In the drawings and specification there has 20 been set forth a preferred embodiment of the invention, and although specific terms are employed, they are used in a generic and descriptive sense only, and not for purposes of limitation, the scope of the invention being set forth 25 in the appended claims.

I claim:

1. A flashing block having a horizontally disposed and upwardly inclined slot provided with a substantially horizontally disposed enlargement 30 at the upper end of the inclined slot provided with a projection extending from the roof of the enlargement for engaging the upper end of a flashing bent upon itself when the flashing is moved upwardly in the inclined slot, so that a tool can be inserted over the end of the flashing bent upon itself for removing the flashing from the cavity.

2. In combination, a building block provided with an open slot extending the length of the 40 block and being inclined inwardly and upwardly and terminating in a cavity which is broader than the slot and forming a shoulder above the inclined slot, a flashing strip for disposition through said slot and into said cavity and having its upper end bent upon itself to bear against said shoulder when the strip is partially withdrawn from said slot to prevent further withdrawal of the flashing strip from said slot, said cavity having a downwardly projecting portion 45 extending from the roof of the cavity for engagement with the bent portion of the flashing strip when it is moved upwardly in said inclined slot to allow the tool to be inserted above said bent 50 portion for removing the strip from the cavity and from said slot.

3. A building block for roof flashing adapted to be laid in a wall with its exterior face flush with the surface of said wall, said block having 60 a slot therein to receive the flashing and said slot having a reentrant portion extending into the body of the slot to receive a projection on said flashing and cam means disposed within the slot for releasing said flashing from said block.

4. A flashing block for the roof flashing used in building construction, said block having a flashing receiving slot therein extending in a plane at an angle to the exposed face of the block, said slot having a reentrant recess in 70 which a locking projection on said flashing is received with means disposed in said slot for automatically releasing said projection so that it may be removed from the block.

5. A block for roof flashing used to cover a 75

joint in building construction, said block having a slot therein off-set with respect to the plane in which the exposed face of the block is located and a reentrant recess merging into said slot, a lip at the entrance of said reentrant portion to receive a projection on said flashing

whereby the projection on the flashing extending into the slot will be flexed by said lip, and cam means disposed within the slot for releasing said flashing from said lip.

WILLIAM F. COX. 5
